CLAIM

The ornamental design for an artificial log assemblage for a gas-fired fireplace, as shown and described.

DESCRIPTION

FIG. 1 is a front elevational view of an artificial log assemblage for a gas-fired fireplace, showing my new design;

FIG. 2 is a top plan view thereof;

FIG. 3 is a left-side elevational view thereof;

FIG. 4 is a right-side elevational view thereof;

FIG. 5 is a rear elevational view thereof;

FIG. 6 is a bottom plan view thereof.

The broken-line showing of environmental structure in FIG. 1 is for illustrative purposes only, and forms no part of the claimed design.

FIG. 1

FIG. 2

FIG. 3

FIG. 4

FIG. 5

FIG. 6
